UNITED STATES PATENT OFFICE

159,452

TOY CATAFALC BODY OR SIMILAR ARTICLE

Carl W. Sundberg, Birmingham, Mich., assignor
to Hercules Powder Company, Wilmington, Del.,
a corporation of Delaware

Application May 18, 1949, Serial No. 2,738

Term of patent 14 years

(Cl. D34—15)

To all whom it may concern:

Be it known that I, Carl W. Sundberg, a citizen of the United States, residing at Birmingham, in the county of Oakland and State of Michigan, have invented a new, original, and ornamental Design for a Toy Catapult Body or Similar Article, of which the following is a specification, reference being had to the accompanying drawing, forming a part thereof.

In the drawing:

Fig. 1 is a top view of a toy catapult body or similar article embodying my new design;

Fig. 2 is a front view;

Fig. 3 is a side view; and

Fig. 4 is a perspective view thereof.

The dominant features of my new design are shown in solid lines in the drawing, the broken line showing of the dart and rubber band projector being for illustrative purposes only.

I claim:

The ornamental design for a toy catapult body or similar article, substantially as shown and described.

CARL W. SUNDBERG.
